UNITED STATES PATENT OFFICE

BROWN F. DE GRAW, OF FORT WAYNE, INDIANA, ASSIGNOR TO THE WESTERN GAS CONSTRUCTION CO., A CORPORATION OF INDIANA

GAS MANUFACTURE

Application filed April 15, 1929. Serial No. 355,054.

This invention relates to gas manufacture and particularly to charging machines for gas producers.

With the ordinary bell type of charger a slight amount of segregation may take place inside the bell before the bell opens. If any fine fuel is mixed in with fairly large lumps, the fine fuel can sift down toward the lower edge of the bell or cone. As the bell opens, the first fuel passing out is necessarily retarded due to the narrowness of the partial opening and would ordinarily be the fines if any should be present near the edge of the bell. When the bell is entirely open, the remaining fuel slides off the conical surface without being retarded by a narrow opening so that any fines which have sifted to the bottom of the bell chamber are dropped off the bell with slight velocity and fall near the center of the gas producer while the remainder of the charge is deposited away from the center.

When a mixture of coarse and fine fuel slides off the surface of the bell, a sorting out takes place on the way to the top of the fuel bed for the fine pieces of fuel are checked by the gases through which they pass while the larger pieces will have sufficient momentum to be carried to a greater radial distance from the center of the furnace.

If the bell is small enough to deposit an appreciable amount of fuel at the exact center of the producer, then it is likely that it will build up a mound of fuel near the center of the producer. Should this occur, the larger pieces of fuel will roll from the high center to the lower edges of the top of the fuel bed.

Such segregation of the fuel results in the fire burning more freely at the edges of the producer than at the center because of the larger spaces between the coarser pieces of fuel. Should even a slight difference of this kind occur, the fuel is consumed more rapidly near the edges than near the center and the outer edge of the top of the fuel bed sinks the more rapidly, thereby increasing the rolling of the larger pieces on the top of the fuel bed towards the edges of the producer,

thus further increasing the degree of segregation.

Attention is called to the fact that most of the above-mentioned factors that tend to produce a sorting out of the fuel are all cumulative as each tends to leave the fine fuel at the center and deposit the coarser fuels at the edges of the fuel bed.

The charging machine of my invention consists of a rotatable hopper in the top of the producer which scatters the fuel by centrifugal force as it is fed into the producer. More particularly, it consists of a hopper projecting into the generator and occupying about the same location as the customary bell charger and is provided with doors at the lower edge which open when the hopper is revolved by a motor. The fuel is projected radially from the open doors.

While the rotatable hopper forming the subject matter of this invention may have tendencies to segregate the fine from the coarse particles, not all of such tendencies are cumulative nor tend in the same direction.

When a mixture of different-sized pieces are projected by centrifugal force, the larger pieces are less affected by air or gas resistance than the smaller pieces. On the other hand, the bell may be so accelerated as to deposit the bulk of the fuel towards the edges of the generator and then any rolling action of the pieces from the higher edges to the lower center would tend to segregate the larger pieces in the center. That is, if the gas resistance tends to segregate the smaller pieces toward the center and if the rolling on the sloping surface tends to segregate the larger pieces near the center, then these two errors of operation tend to neutralize each other.

In the drawing, the single figure is a vertical cross-sectional view of a portion of a producer provided with a charging machine of my invention.

A rotatable charging hopper 1 that is mounted in the top of a gas producer 2 has flap valves or doors 3 at its lower edge which are suspended by means of hinges 4. Vertical ribs 5 support a bottom 6 for the hopper 1.

which rotates freely on bearings 7. The bottom 6 is conical whereby the downwardly inclined sides facilitate the discharge of coal from the hopper.

5 A flange 8 at the upper edge of the hopper has bevel gear teeth that are engaged by a bevel pinion 9 mounted on a shaft 10 passing through a bearing 11 that serves as a stuffing gland. A casing 12 attached to the top of the generator completely surrounds the mechanism just described to make the top of the generator gas tight. A sliding door 13 admits charges to the hopper 1 and a floor 14 is provided at a convenient height.

15 When the door 13 is opened, a weighed amount of fuel that has previously been placed on the surface of belt 15 is deposited through funnel 16 into the rotatable hopper. Between charging periods a feed belt 17 with 20 the aid of a weighing machine, indicated generally at 18, deposits the exact weight of fuel required for the next charge upon the weighing belt 15.

The operation of the device is as follows:

25 The weighing belt 15 is suspended on knife edges (not shown) and moves forward very slowly while a charge of coal is being weighed out. At this time, feed belt 17 deposits coal from the weighing machine 18 upon belt 15 30 until the scale beams (not shown) attached to the knife edges on which belt 15 rests are moved whereupon through appropriate automatic electric connections the movement of belt 17 is stopped and also the slow motion 35 of belt 15 is stopped.

At the proper time to deposit the fuel in the rotatable hopper 1, a motor (not shown) slides the door 13 out of the way and belt 15 moves forward, depositing the entire charge 40 into hopper 1, whereupon the belt 15 is stopped and sliding door 13 moved to close the top of hopper 1.

45 While the door 13 is open, the doors 3, which are closed, operate to prevent the escape of gas from the interior of the producer into the atmosphere. The doors are biased to their closed positions by the pressure of the gas in addition to the force of gravity.

50 The doors 3 operate also to retain the charge of fuel in the hopper while the latter is at rest. This feature is desirable in order that the fuel may be admitted to the producer periodically in accordance with the charging schedule.

When it is time to charge the contents of the hopper 1 onto the fuel bed in the producer 2, the electric motor (not shown) that is connected to the shaft 10 at the upper edge 60 of the hopper is started, causing the hopper to revolve whereupon centrifugal force opens the doors 3 and the fuel is thrown out of the bottom of the hopper radially and scattered over the upper surface of the fuel bed.

65 It will be noted that I have provided a

charging device for gas producers that operates automatically to distribute fuel charged therein in such manner as to neutralize the tendency of fuel of various sizes to segregate or to accumulate faster in certain portions of the fuel bed than in other portions. 70

Also the charging device operates to retain the fuel therein until it is released at desired times. The same movable closures for retaining the fuel also prevent the escape of gas when the hopper is being provided with a charge of fuel. 75

I claim as my invention:

1. A charging device for gas producers comprising a rotatable hopper for receiving fuel, doors for said hopper that are normally closed, and means for rotating said hopper to cause said doors to open and to distribute the fuel contents of said hopper. 80

2. A charging device for gas producers comprising a rotatable hopper in the upper portion of a producer and having openings in the bottom portion thereof, doors for said openings normally closed by gravity to retain the charge within said hopper, and means for rotating said hopper to open said doors by centrifugal force and to distribute the charge substantially radially of said hopper. 85

3. A charging device for gas producers comprising a hopper for fuel having an upper closure and a lower closure for opening into a producer and normally closed by gravity and the pressure of gas within said producer, and means for rotating said hopper to open said lower closure by centrifugal force to distribute the fuel contents of said hopper. 90

4. In a gas producer, the combination of a 95 hopper for receiving material for charging the same, means for rotating the hopper, and doors at the lower end of the hopper for retaining said material but adapted to be opened by centrifugal force when the hopper is rotated. 100

5. In a gas producer, the combination of a charging hopper projecting through the top of the producer into its interior, means at the top of the hopper for rotating the same, and a normally closed closure at the bottom of the hopper for preventing flow of gas into said hopper while the latter is at rest and for opening to admit fuel to said producer while the hopper rotates. 115

6. In a gas producer, the combination of a charging hopper projecting into the upper part of the producer and adapted to receive fuel, a ring attached to the upper part of the hopper having a bearing and gear mechanism for rotating the hopper, a floor supported by a plurality of ribs at the lower end of the hopper for supporting the charge and a plurality of doors adapted to close openings between the ribs when the hopper is at rest. 125

and to open into said producer to discharge said fuel when the hopper is rotated.

7. In a gas producer, the combination of a rotatable charging hopper at the top there-
5 of for receiving fuel for said producer and doors at the lower portion of the hopper that are normally closed but are adapted to be opened by centrifugal force to discharge said fuel while the hopper is rotating.

10 In testimony whereof, I have hereunto sub-
scribed my name this 6th day of April 1929.
